PHOTOGRAPHIC PRINT DRIER

Carter J. Hughey, Rochester, N. Y., assignor, by
mesne assignments, to Eastman Kodak Company,
Jersey City, N. J., a corporation of New Jersey

Application February 13, 1935, Serial No. 6,350

6 Claims. (Cl. 34—26)

This invention relates to driers, particularly for use in drying photographic prints. One object of my invention is to provide a drier which can be quickly and easily operated and which is adapted to receive prints in stacks for drying. Another object of my invention is to provide a drier with an air-circulating system which can be readily adjusted to efficiently dry varying numbers of prints. Another object of my invention is to provide an air-circulating system with air distributing plates which will increase the efficiency of the drier. Still another object of my invention is to provide a drying cabinet with a slidable support for an air-circulating casing so that the relation of the casing to the drying cabinet can be altered at will, and other objects will appear from the following specification, the novel features being particularly pointed out in the claims at the end thereof.

Coming now to the drawings wherein like reference characters denote like parts throughout:

Fig. 1 is a side elevation of a drier constructed in accordance with and embodying a preferred form of my invention.

Fig. 2 is an end elevation of the drier shown in Fig. 1.

Fig. 3 is an elevation from the opposite end of the machine shown in Fig. 2.

Fig. 4 is an enlarged fragmentary section taken on line 4—4 of Fig. 3.

Fig. 5 is an enlarged fragmentary section showing the relation of the prints and print separators.

As indicated in Fig. 1, the drier may comprise a table-top 1 supported by legs 2 and carrying a cabinet composed of sections 3 and 4 which are preferably hinged together at 5. As best shown in Fig. 2, the table-top 1 is provided with a concave top wall 6, this wall being arranged to receive a stack of print separators, blotters, and prints.

Referring to Fig. 5, the prints P are laid preferably face down on the linen sheets 7 with blotters 8 lying against one side of the print and 45 with separators designated broadly as 9 lying between the prints. The separators may be made of corrugated board which includes the sheets 10 and 11 separated by the corrugated wall 12. These separators and blotting paper are known 50 to the trade and are used for drying because air can be circulated through and between the prints held by these members. The advantage of having the curved wall 6 is that the stack of prints, separators, and blotters will all be held in a 55 curved condition while the prints are being dried.

and since the sensitized side of the print lies against the convex wall of the separators or the linen covering thereof, the prints are bent and dried in such a position that they will tend to lie flat.

On section 4 of the cabinet, handles 13 are provided to facilitate swinging this section on the hinge 5 until the top 14 rests on the top 15 of section 3. The stack of prints, blotting papers, and separators can then be laid upon the 10 curved table-top 6 and slid toward the opposite end of the machine until the stack strikes the flanges 14 as shown in Fig. 5.

Since the size of the stack may vary in accordance with the number of prints to be dried, 15 in order to efficiently pass air over the desired area, the following structure is provided. Section 3 of the cabinet is provided with guide rails 16 shown on an enlarged scale in section in Fig. 4. These guide rails are preferably spaced apart, 20 as shown, to receive a flange 17 carried on the inner edges of a housing 18 which is open on that side which faces the cabinet 15 and which is provided with an extension 19 in which a fan 20 is mounted, there being a motor 21 carried by the 25 bracket 22. Inside of the housing 18 there are plates 23 which, as shown in Fig. 3, are arranged about a square opening 24 set at an angle to the end of the housing 18. Posts 25 may conveniently support electric heating elements 26 30 which are suspended from the cross-bars 27 and which may be connected to a suitable switch 28 as shown in Fig. 3. Thus, air is blown by the fan so that it will pass through the open end of cabinet section 15 through the stack and out 35 through the openings 29 in section 14 of the cabinet.

The top wall of the housing 18 is provided with a second curved wall 30 which conforms in curvature with the curved wall 6 of the table-top. 40 This wall can be raised and lowered so that an extension thereof 31 which extends inside of the cabinet section 15 can be brought into contact with or close to the stack carried by the table-top. Thus, as illustrated in Fig. 5, when the 45 stack does not completely fill the drying cabinet, the housing 18 may be slid downwardly upon the rails 16 until the plate 30 lies close to the uppermost sheet of the stack.

In order to accomplish this movement, at least 50 one rail 16 is provided with a series of perforations 34 preferably formed in raised flanges 35 formed in the rails 16. As indicated in Fig. 4, the housing 18 may be held in the desired position by means of a latch 36 which is merely a 55

plunger pressed by a spring 37 towards the apertures 34 and having a handle 38 by which the plunger may be removed from these apertures.

After loading the table-top 6 with the desired number of prints, separators, and blotting papers, the plungers 38 are withdrawn and the housing 18 is slid downwardly until the plate 30 lies close to the uppermost sheet of the stack. This will automatically cause all of the air blown through the housing 18 by the fan 20 to pass through the stack which is actually being used and none of the air will pass idly over the top of the stack, as would be the case if the housing 18 was fixedly attached to the cabinet section 15. Thus, if only half of the capacity of the drier is in use, the housing 18 could be slid down from the positions shown in Figs. 1 and 3 until the fan was centered on the stack actually being used.

20 The operation of this print drier is extremely simple. Cabinet section 14 is swung about the hinged pintle 5 in the direction shown by the arrow in Fig. 1 until the top 14 rests on the top 15. The operator then places the separators, prints, and blotting papers on the curved table-top 6 until the machine is completely loaded. Cabinet section 14 is then swung down to its operative position shown in Fig. 2 and the plungers 38 are withdrawn from apertures 34 and the housing 18 may be moved upon the rails 16 until the curved top wall 30 approaches the top of the stack held by the table. The plungers then are permitted to enter the nearest apertures to hold the housing 18 in the set position and the motor is started. If it is necessary to dry the prints quickly, the switch 28 can be moved to cause the heating elements 26 to function so that warm air may be blown between the separators and dry the prints.

40 After the prints have been dried, section 14 can again be swung on its hinge 5 to open the cabinet for the removal of the dried prints.

Having thus described my invention, what I claim as new and desire to secure by Letters 45 Patent of the United States is:

1. In a photographic print drier, the combination with a cabinet adapted to hold stacks of prints in spaced relation, a slideway on the cabinet, a casing mounted to move in the slideway, means to hold the casing in a set position, a blower in the casing and means carried by the casing for directing air through a restricted area of the drying cabinet, said means including a baffle plate, a flange on the plate adapted to project over the stack of prints carried by the cabinet whereby air may be directed to the area of the cabinet in use.

2. In a photographic print drier, the combination with a cabinet including a table-top, of a casing enclosing the table-top and including top, side and end walls, said casing being divided into two sections each including a portion of the top, side and end walls and hinged together on the top wall, one section being permanently attached to the table and the other being adapted to move

on the hinge to expose a relatively large area of the table for loading stacks of prints on the table-top, and means including a blower movably carried by the fixed casing section for directing air over only that area of the cabinet 5 filled with stacks of prints.

3. In a photographic print drier, the combination with a cabinet including a table-top, of a casing enclosing the table-top and including top, side and end walls, said casing being divided into two sections each including a portion of the top, side and end walls and hinged together on the top wall, one section being permanently attached to the table and the other being adapted to move on the hinge to expose a relatively large area 10 of the table for loading stacks of prints on the table-top, and means including a blower at least partially enclosed in a separate casing slidably mounted on the fixed section for directing air to a predetermined area of the drier.

4. In a photographic print drier, the combination with a cabinet including a table-top, of a casing enclosing the table-top, said casing being divided into two sections hinged together, one section being permanently attached to the 15 table and the other being adapted to move on the hinge to expose a relatively large area of the table for loading stacks of prints on the table-top, and means including a blower at least partially enclosed in a separate casing, a vertical 20 slideway on the fixed section engaged by the motor casing whereby air may be directed from the fan to the vertical area of the drier actually in use.

5. In a photographic print drier, the combination with a cabinet including a concave table-top adapted to receive a stack of prints, blotters, and separators in concave stacks, of a casing adapted to enclose said table-top, an air exit at one end of the cabinet, an air entrance at the 40 other end thereof, a support, a blower carried thereby for forcing air in the air entrance, and adjustable means for controlling the area of the air entrance in accordance with the size of the stack of prints, blotters, and separators and 45 including a curved flange adapted to be close to the curved top of the stack of prints, blotters, and separators.

6. In a photographic print drier, the combination with a cabinet including a concave table-top adapted to receive a stack of prints, blotters, and separators in concave stacks, of a casing adapted to enclose said table-top, an air exit at one end of the cabinet, an air entrance at the other end thereof, a support, a blower carried 50 thereby for forcing air in the air entrance, and adjustable means for controlling the area of the air entrance in accordance with the size of the stack of prints, blotters, and separators and including a curved flange adapted to be close to the curved top of the stack of prints, blotters, and separators, and spring latch elements carried by the blower support and fixed casing for holding the former in a set position.

CARTER J. HUGHEY.
